The ornamental design for a jewelry chain, as shown and described.

DESCRIPTION

FIG. 1 is a perspective view of a first embodiment of a jewelry chain showing our new design, such first embodiment ment formed from solid chain links having rectangular cross sections as shown in FIG. 5;

FIG. 2 is a cross section taken through a link of the jewelry chain along line 2—2 of FIG. 1;

FIG. 3 is a cross section thereof taken through line 3—3 of FIG. 1;

FIG. 4 is a cross section taken through line 4—4 of FIG. 1 representing a second embodiment of a jewelry chain showing our new design, such second embodiment formed from hollow chain links having rectangular cross sections as shown in FIG. 6, with the chain view and cross section of a link view of such second embodiment being identical in appearance to the chain and cross sectional views of FIGS. 1 and 2 from the first embodiment;

FIG. 5 is a cross section taken through line 5—5 of the link of FIG. 2 of the first embodiment of the jewelry chain of our design;

FIG. 6 is a cross section taken through line 6—6 of the link of FIG. 2 of the second embodiment of the jewelry chain of our design;

FIG. 7 is a perspective view of a third embodiment of a jewelry chain showing our new design, such third embodiment formed from solid chain links having square cross sections as shown in FIG. 11;

FIG. 8 is a cross section taken through a link of the jewelry chain along line 8—8 of FIG. 7;

FIG. 9 is a cross section thereof taken through line 9—9 of FIG. 7;

FIG. 10 is a cross section taken through line 10—10 of FIG. 7 representing a fourth embodiment of a jewelry chain showing our new design, such fourth embodiment formed from hollow chain links having square cross sections as shown in FIG. 12, with the chain view and cross section of a link view of such fourth embodiment being identical in appearance to the chain and cross sectional views of FIGS. 7 and 8 from the third embodiment;

FIG. 11 is a cross section taken through line 11—11 of the link of FIG. 8 of the third embodiment of the jewelry chain of our design; and,

FIG. 12 is a cross section taken through line 12—12 of the link of FIG. 8 of the second embodiment of the jewelry chain of our design.
